UNITED STATES PATENT OFFICE.

STANTON E. MALLERY, OF SYRACUSE, NEW YORK, ASSIGNOR TO OLIVER M. EDWARDS,
OF SYRACUSE, NEW YORK.

EXTENSION SPRING-ROLLER

1,077,149.

Specification of Letters Patent.

Patented Oct. 28, 1913.

Application filed May 29, 1911. Serial No. 630,041.

To all whom it may concern:

Be it known that I, STANTON E. MALLERY, of Syracuse, in the county of Onondaga and State of New York, have invented a certain 5 new and useful Extension Spring-Roller, of which the following is a specification.

This invention has for its object the production of an extension spring roller for raising curtains, windows, etc., which is particularly simple in construction, economical in manufacture, and highly efficient and durable in use; and the invention consists in the combinations and constructions herein-after set forth and claimed.

15 In describing this invention reference is had to the accompanying drawing in which like characters designate corresponding parts in all the views.

Figure 1 is a longitudinal sectional view 20 of my spring roller. Fig. 2 is a cross sectional view thereof, on line "A—A," Fig. 1. Figs. 3 and 4 are end views of the telescoping portions of the roller.

This extension spring roller comprises, 25 generally, sections having telescoping tubular portions, the inner tubular portion being expansible and contractile and formed of resilient material in order to clamp the same within the outer tubular portion.

30 1 and 2 are the sections of the roller, the section 1 having tubular portion 3 in which telescopes the tubular portion or extension member 4 secured to the section 2. The major parts of the sections 1 and 2 are preferably of equal diameter and the portion 4 of the section 2 also telescopes within the major part of the section 2 and is fixed therein in any suitable manner.

The sections 1, 2 are preferably tubular 40 throughout their entire length and the portion 3 of the section 1 is integral with the remaining portion of such section 1.

The major parts of the sections 1 and 2 of the roller are provided with a peripheral 45 lengthwise depression 5 which forms an external channel and an inwardly extending rib extending the full length of said major parts, the portion of the channel in the section 2 being aligned with the portion of the 50 channel in the section 1. The channel

formed by the depression 5 is for the purpose of receiving the edges of the curtain, or the means of attachment of the roller to a window, as will be understood by those skilled in the art.

The inner tubular portion 4 of the section 2 is split longitudinally in order to render the same expansible and contractile and is bent to conform to the internal rib formed by the depression 5.

In the illustrated embodiment of my invention the lengthwise flanges or margins 6, 7 on opposite sides of the line of division of the tubular portion 4, are bent to conform to the rib and one of such margins, as the 65 margin 6, is designed to overlap the margin 7 when the tubular portion 4 is fitted within the portion 3 of the section 1. After the portion 4 has been inserted in the portion 3 of the section 1, the section 2 is moved endwise until the roller is of proper length and the telescoping portions are then permanently secured together by forming interfitting indentations in the telescoping portions as illustrated at 8. The sections 1, 2 70 are also provided with suitable axles or trunnions 9 and 10, the axle 9 being designed to be held stationary in the normal use of the roller, and being connected to one end of a spring 11 extending axially of the 75 section 1, such spring being connected at its other end to an anchor 12 located within the section 1. The axle 10 is designed to rotate with the section 2 as will be understood by those skilled in the art.

This extension spring roller is particularly advantageous in that it can be quickly adjusted to the desired length and parts thereof permanently secured together.

What I claim is:

An extension spring roller comprising two tubular sections having corresponding lengthwise depressions forming peripheral channels, and internal beads, or ribs, and an extension member comprising a split bar 95 having contiguous longitudinal edges provided with inwardly extending flanges designed to overlap each other, and curved to substantially conform to the cross-sectional shape of said beads, or ribs, said bar- 100

2
rel being carried by one of said sections and telescoping within the other of said sections and being held in place therein by complementary indentations and depressions, substantially as and for the purpose described.

In testimony whereof, I have hereunto signed my name in the presence of two at-

testing witnesses, at Syracuse, in the county of Onondaga, in the State of New York, 10 this 22nd day of May, 1911.

STANTON E. MALLERY.
